UNITED STATES PATENT OFFICE.

PHILIP A. MYERS, OF ASHLAND, OHIO, ASSIGNOR TO F. E. MYERS & BRO., OF ASHLAND, OHIO, A COPARTNERSHIP.

HAY-TOOL.

SPECIFICATION forming part of Letters Patent No. 739,901, dated September 29, 1903.

Application filed July 16, 1903. Serial No. 165,768. (No model.)

To all whom it may concern:

Be it known that I, PHILIP A. MYERS, a citizen of the United States, residing at Ashland, in the county of Ashland and State of Ohio, have invented certain new and useful Improvements in Hay-Tools, of which the following is a specification, reference being had therein to the accompanying drawings.

This invention relates to improvements in hay-tools, and more specifically to what are known as "compression-sling" attachments, being in the nature of a device for use in connection with a sling to enable the same to be used in connection with a carrier in the place of a fork.

The object of the invention is to provide a device which may be used in connecting any form of an ordinary hay-carrier without making any change whatever except disconnecting the hay-fork from the fork-pulley and substituting the attachment which I have devised, using the same in connection with a suitable sling.

To these ends my invention consists in certain novel features which I will now proceed to describe and will then particularly point out in the claims.

In the accompanying drawings, Figure 1 is a perspective view of a structure embodying my invention in one form. Fig. 2 is a vertical sectional view of the same, taken on the line xx of Fig. 3 and looking in the direction of the arrows. Fig. 3 is a vertical section view taken on the line yy of Fig. 2 and looking in the direction of the arrows. Fig. 4 is a perspective view illustrating the device applied to a sling, showing the position of the parts at the beginning of the operation of compressing the bundle; and Fig. 5 is a similar view showing the position of the parts after the fork-pulley has passed through the attachment, the bundle being compressed.

Referring first more particularly to Figs. 1, 2, and 3, which show the attachment in detail, it may be stated that while these details, which I will now proceed to describe incidentally to the description of the general structure of the device, are deemed desirable features the present invention is in no way restricted to said details of construction.

The attachments comprise a bail or loop 1,

having the form of a yoke or arch and preferably made in two separate pieces united by screw-bolts 2 and 3. The arched end of the bail, which may for convenience sake be termed the "lower" end, is provided with a projection 4, terminating in a hook 5, and it is at this end that the screw-bolts 2 are located. The separated ends of the parallel arms of the bail at what may be conveniently termed the "upper" end of the attachment are united by the screw-bolt 3, which is provided at each end with a nut 6, seated in a recess 7 in the center of a disk-like enlargement 8 at the end of each arm of the bail. 65 A sleeve 9 surrounds the bolt 3 and serves as a spacing device to keep the ends of the bail apart and also as a bearing-sleeve for the roller which is located at the upper end of the bail. This roller is preferably made in three sections—to wit, a central section 10 and two end sections 11—each of which is provided at its outer end with an inclined flange 12, which fits against the corresponding disk-like enlargement 8, these latter being preferably of slightly greater diameter than said flanges 12.

In connection with the bail or loop 1 I employ a pivoted arm 13, serving both as a separator to separate the leads of the rope and as a support for the guide-pulleys, over which said leads travel during a portion of the time. This arm is pivotally connected with the bail or loop near that end thereof which is provided with the roller, and I prefer to pivot it on the same axis as said roller—to wit, the sleeve 9 and bolt 3. To this end the arm 13, which is in the form of a U-shaped frame having two parallel members 14 and a cross or connecting piece 15, is provided at the upper ends of the members 14 with annular portions or eyes 16, which fit upon the sleeve 9 between the rollers 10 and 11, as shown in Fig. 2. Near its other or lower end the arm 13 is provided on each side with a guide-pulley 17, supported in a bracket 18, preferably integral with the arm 13. Each bracket 18 preferably extends some distance beyond its pulley, as indicated at 19, to form a guard therefor and to maintain the rope in proper position on the pulley. It will be noticed that the guide-pulleys 17 are located at some dis-

tance from the roller and at or near the opposite end of the arm from that nearest the roller.

Provision is made for locking the arm 13 in the central position relatively to the loop or bail 1, (shown in Figs. 1 to 4, inclusive,) and for this purpose I prefer to employ a locking-bolt 20, adapted to slide longitudinally of the arm in suitable guideways therein. 5 These guideways are formed in the present instance by an aperture 21 in the connecting-piece 15 of the arm 13 and an aperture 22 in a cross-piece 23, forming a part of said arm 13. That portion of the bolt 20 which passes 10 through the aperture 21 is preferably rectangular in cross-section, the aperture 21 being similarly shaped to fit the bolt and prevent its turning. The rear end of the bolt 20 is in the form of a cylindrical shank 24 of 15 reduced diameter, fitting the aperture 22, which is made circular for this purpose. The reduction of the shank forms on the bolt a shoulder 25, which shoulder constitutes an abutment for one end of a spring 26, coiled 20 around the shank 24 of the bolt and bearing at its other end against the cross-piece 23 as an abutment. A pin 27, passing through the shank 24 above the cross-piece 23, may be employed to limit the outward movement of the 25 bolt before the tripping device, hereinafter referred to, is applied thereto or in case the tripping device becomes broken. Co-operating with the bolt 20 is an aperture 28 in the inner face of the loop or bail 1, so that the 30 engagement of the bolt in said aperture locks the arm 13 in central position. To make the bolt self-locking, its end is rounded or beveled, as indicated at 29, and the inner surface of the bail 1 is similarly rounded or beveled at each side, as indicated at 30.

The tripping device, hereinbefore referred to, consists of two plates 31, pivoted on an axis 32, carried by the arm 13 in the upper portion thereof, said plates extending downward between and past the pulleys 17 and having their marginal portions bent outward, as indicated at 32^a. These plates are connected by means of a V-shaped cam-piece 33, by which they are rigidly united; and, in fact, 45 said plates and cam-piece may be considered as a single piece and may be so constructed, said parts constituting the trip-arm. The cam-piece 33 passes through a slot 34 in the rectangular body portion of the bolt 20 and 50 said cam-piece bears against a roller or other suitable abutment 35, carried by the bolt 20 within said slot. In the present instance I have shown the abutment as consisting of a roller 35, as just stated, said roller being carried by a pin 36, which may be placed in any one pair of a series of apertures 37, formed in the bolt 20 to receive the same. By shifting the pin 36 the tension of the spring 26 may be varied, as well as the extent to which 55 the bolt 20 projects into the aperture 28. To accommodate a maximum amount of projection of the bolt and at the same time save

metal and lighten the casting, the projection 4 may be hollowed out to form a chamber, as indicated at 38.

It will be noted that when the arm 13 is locked in a central position the roller 35 bears in the center or angle of the V-shaped cam-piece 33. If pressure be applied to either one of the plates 31, so as to move the trip-arm in one direction or the other, the cam-piece will bear against the roller 35 in such a way as to force the bolt 20 back and withdraw it from the aperture 28, thus unlocking the arm 13.

In Figs. 4 and 5 I have shown my improved attachments as connected to a sling and operating in connection with a fork-pulley and rope of a hay-carrier of ordinary construction. One end of the sling (indicated by the reference-numeral 39) is connected to the hook 5 of the attachment. The other end of the sling (indicated by the reference-numeral 40) is connected to the hook 41 of the fork-pulley 42. The rope leading from the fork 90 to the carrier is indicated by the reference-numeral 43, and it will be seen that during the first portion of the operation of drawing the sling around the bundle of hay the two leads of the rope 43 travel around the guide-pulleys 17, being separated by the arm 13, so as to keep the leads clear of each other and cause them to run freely around said guide-pulleys. During this portion of the operation the rope 43 does not run on the roller at 95 the end of the yoke, but on separate guide-pulleys located at some distance from said roller. As the bundle is compressed the fork-pulley 42 approaches the attachment and finally strikes the tripping-arm. In this connection it will be noted that the tripping-arm is in duplicate, having a contact-plate 31 on each side of the attachment, so that the attachment is reversible, and it makes no difference which side is presented to the advancing fork. In practice these fork-pulleys are usually provided with a so-called "registering head" 44, and it is this head that first strikes the tripping-arm. The flange 32^a of the tripping-plate 31 is of material advantage 100 in this connection in preventing the end of the fork-pulley from sliding or glancing off of said plate without moving the tripping-arm in the desired manner. When the tripping-arm is thus struck, it withdraws the bolt 20 in the manner already described, and thus frees the arm 13, which will swing up out of the way, as indicated in Fig. 5, and will leave the loop or bail 1 free and unobstructed in its interior to permit the passage through the 105 same of the fork-pulley 42. After the fork-pulley has passed through the loop, the rope or bridle 40, which constitutes the end of the sling attached to the fork-pulley, travels over the roller at the end of the loop in the 110 usual manner.

In attachments of this character as heretofore constructed the fork-pulley rope 43, the fork itself, and the bridle-rope 40 have all

traveled over the roller at the end of the loop or bail, such a construction being shown, for instance, in Letters Patent No. 554,136, granted to me February 4, 1896. While such a construction is a satisfactory one as a rule, the diversity of hay-carriers and the different sizes and shapes of their fork-pulleys are such that in practice the fork-pulley has been found to occasionally lodge upon the roller or in the bail, thereby preventing it from passing through the bail and moving on up to the carrier, where it should register or lock itself in the manner usual in devices of this description. My improved attachment provides a remedy for this difficulty in that the leads of the fork-pulley rope are first carried around guide-pulleys separate and distinct from the roller and located at a considerable distance therefrom in advance thereof, so that the fork-pulley is brought opposite the opening of the bail in such a position that when the arm 13 is released said fork-pulley passes freely through said opening in the bail and does not have to be dragged around the roller at the end of the bail. In this way lodging of the fork-pulley against the roller or against the body of the bail is prevented, and the attachment is thus adapted for use in connection with a wide range of fork-pulleys of different sizes and shapes and is, in fact, successfully operative with any devices of that character on the market.

I do not wish to be understood as limiting myself strictly to the precise details of construction hereinbefore described and shown in the accompanying drawings, as said details may be obviously modified without departing from the principle of my invention.

Having thus fully described my invention, what I claim as new, and desire to secure by Letters Patent, is—

1. A compression-sling attachment for hay-carriers, comprising a loop or bail, a separating-arm carried thereby and movable relatively thereto, guide-pulleys carried by said arm, means for locking said arm within the loop, and means for releasing said arm to permit it to move clear of the loop, substantially as described.

2. A compression-sling attachment for hay-carriers, comprising a loop or bail, a separating-arm carried thereby and movable relatively thereto, guide-pulleys carried by said arm, means for locking said arm within the loop, and a trip actuated by the fork-pulley for automatically releasing said arm to permit it to move clear of the loop, substantially as described.

3. A compression-sling attachment for hay-carriers, comprising a loop or bail, a separating-arm pivoted therein, guide-pulleys carried by said arm, means for locking said arm within the loop, and means for releasing said arm to permit it to swing clear of the loop, substantially as described.

4. A compression-sling attachment for hay-carriers, comprising a loop or bail, a separating-arm pivoted therein, guide-pulleys carried by said arm, means for locking said arm within the loop, and means for releasing said arm to permit it to swing clear of the loop, substantially as described.

ing-arm pivoted therein, guide-pulleys carried by said arm, means for locking said arm within the loop, and a trip actuated by the fork-pulley to automatically release said arm and permit it to swing clear of the loop, substantially as described.

5. A compression-sling attachment for hay-carriers, comprising a loop or bail having a roller at one end, a separating-arm pivoted to the loop at said end and provided at its other end with guide-pulleys, means for locking said arm within the loop, and means for releasing said arm to permit it to swing clear of the loop, substantially as described.

6. A compression-sling attachment for hay-carriers, comprising a loop or bail provided at one end with means for connecting it to a sling, and at the other end with a transverse roller, a separating-arm pivoted on a common axis with said roller and adapted to lie within the loop, said separating-arm being provided with guide-pulleys on opposite sides thereof at a distance from said axis, means for locking said arm within the loop, and a trip actuated by the fork-pulley to automatically release said arm and permit it to swing clear of the loop, substantially as described.

7. A compression-sling attachment for hay-carriers, comprising a loop or bail, a separating-arm pivoted therein, guide-pulleys carried by said arm, a spring-actuated locking-bolt mounted in said arm and adapted to engage the loop and lock the arm within said loop, and a tripping-arm carried by said separating-arm, movable relatively thereto, and provided with a cam-piece to engage and operate the bolt, said tripping-arm being arranged in the path of the fork-pulley, substantially as described.

8. A compression-sling attachment for hay-carriers, comprising a loop or bail, a separating-arm pivoted therein, guide-pulleys carried by said arm, a spring-actuated locking-bolt mounted in said arm and adapted to engage the loop and lock the arm within said loop, and a tripping-arm pivotally connected to the separating-arm and provided with a cam-piece adapted to engage the locking-bolt to operate the same, substantially as described.

9. In a compression-sling attachment of the character described, the combination, with a loop, and a separating-arm pivoted therein and provided with guide-pulleys and a locking-bolt, of a tripping-arm pivoted on the separating-arm and comprising plates lying on opposite sides of the separating-arm, whereby the attachment is rendered reversible, substantially as described.

10. In a compression-sling attachment of the character described, the combination, with a loop, of a separating-arm pivoted therein, said arm being provided with guide-pulleys, and having guard projections co-operating with said guide-pulleys, substantially as described.

11. In a compression-sling attachment of the character described, the combination, with a separating-arm having guiding-apertures, of a locking-bolt mounted to slide in said apertures, provided with a longitudinal slot, and having a roller mounted in said slot, a spring to force said bolt outward, and a tripping-arm provided with a cam-piece extending through said slot and bearing on said roller, substantially as described.
12. In a compression-sling attachment of the character described, the combination, with a loop, and a separating-arm pivoted therein and provided with guiding-apertures, of a spring-actuated locking-bolt mounted in said guiding-apertures and adapted to engage the loop, said bolt being provided with an adjustable abutment, and a tripping-arm provided with a cam-piece against which the bolt is held by its spring, whereby the adjustment of said abutment controls both the extent to which the bolt is projected, and the force of the spring whereby it is projected, substantially as described.
13. In a compression-sling attachment of the character described the combination, with a separating-arm having guiding-apertures, of a locking-bolt mounted to slide in said apertures and provided with a longitudinal slot, a roller extending across said slot and adjustable longitudinally thereof, a spring to force said bolt outward, and a tripping-arm provided with a cam-piece extending through said slot and bearing on said roller, substantially as described.
14. In a compression-sling attachment of the character described, the combination,
- with a loop or bail, a separating-arm pivoted therein and carrying guide-pulleys, and a locking-bolt mounted in said separating-arm, of a tripping-arm for said locking-bolt, comprising a contact-plate lying in the path of the fork-pulley and having its margin upturned, substantially as described.
15. A compression-sling attachment for hay-carriers, comprising a loop or bail, a part carried thereby and movable relatively thereto, pulleys carried by said movable part, means for locking said movable part within the loop, and a trip actuated by the fork-pulley to automatically release the movable part and permit the fork-pulley to pass through the bail, substantially as described.
16. A compression-sling attachment for hay-carriers, comprising a loop or bail, and a movable part normally locked relatively thereto, said loop and movable part having separated bearings for the loop-forming instrumentalities, these latter bearing first upon the bearings of the movable part, and a trip automatically operated by the fork-pulley to release the movable part and permit it to move clear of the loop, the bearing of the loop-forming instrumentalities shifting to the bearings of the loop when the movable part is released, and the fork-pulley passing through the loop during this shifting, substantially as described.

In testimony whereof I affix my signature in presence of two witnesses.

PHILIP A. MYERS.
